CUTLERY HANDLE

Richard T. Hopcraft and Arthur Apissomian, Providence, R.I., assigns to Imperial Knife Associated Companies, Inc., Providence, R.I., a corporation of Rhode Island

Filed Sept. 9, 1969, Ser. No. 19,079

Term of patent 14 years

Int. Cl. D7—03

U.S. Cl. D95—3

FIG. 1 is a side elevational view of a cutlery handle showing our new design;

FIG. 2 is a top plan view;

FIG. 3 is a bottom plan view;

FIG. 4 is a side elevational view of a cutlery handle showing another form of our new design wherein the bolster has been downwardly extended;

FIG. 5 is a right end elevational view of the handle as shown in FIG. 1;

FIG. 6 is a sectional view on line 6—6 of FIG. 1;

FIG. 7 is a sectional view on line 7—7 of FIG. 2;

FIG. 7 is a sectional view on line 7—7 of FIG. 2;

FIG. 8 is a sectional view on line 8—8 of FIG. 2; FIG. 9 is a sectional view on line 9—9 of FIG. 2; and

FIG. 9 is a sectional view on line 9—9 of FIG. 2, and FIG. 10 is a sectional view on line 10—10 of FIG. 1.

We claim:

The ornamental design for a cutlery handle, substantially as shown and described.
